UNITED STATES PATENT OFFICE.

GUY CAMPBELL, OF CREEDMOOR, TEXAS.

CASE FOR RURAL-MAIL CARRIERS.

1,223,474.

Specification of Letters Patent. Patented Apr. 24, 1917.

Application filed May 25, 1916. Serial No. 99,829.

To all whom it may concern:

Be it known that I, GUY CAMPBELL, a citizen of the United States, residing at Creedmoor, in the county of Travis, State of Texas, have invented certain new and useful Improvements in Cases for Rural-Mail Carriers; and I do hereby declare the following to be a full, clear, and exact description of the invention, such as will enable others skilled in the art to which it appertains to make and use the same.

The present invention is directed to improvements in devices for use by rural mail carriers, and has for its object to provide a device of this character so constructed that stamps, envelops and postal cards can be carried in the device so as to be ready for sale to persons along the route.

A further object of the invention is to provide a device of this character which is so constructed that the different articles can be readily removed, and when in their respective compartments will be protected in inclement weather.

With these and other objects in view, this invention resides in the novel features of construction, formation, combination and arrangement of parts to be hereinafter more fully described, claimed and illustrated in the accompanying drawing, in which:

Figure 1 is a front view of the device.

Fig. 2 is a rear view.

Fig. 3 is an end view.

Fig. 4 is a sectional view on line 4—4 of

Fig. 1.

Fig. 5 is a sectional view on line 5—5 of

Fig. 3.

Fig. 6 is a sectional view on line 6—6 of

Fig. 1.

Fig. 7 is a sectional view on line 7—7 of

Fig. 1.

Fig. 8 is a sectional view on line 8—8 of

Fig. 4.

Referring to the drawing 1 indicates the casing, said casing being provided with a horizontal partition 2 which forms in conjunction with the bottom 3 a compartment 4. Extending from the partition 2 and to the top 5 of the casing is a partition 6 which divides the casing 1 into compartments 7 and 8, the latter compartment being comparatively larger than the former.

Hingedly connected doors 9 are provided for the sides 10 of the compartment 8, said compartment being for the purpose of receiving packs of envelops and postal cards

which are arranged so that the postal cards can be removed from one side of the casing while the envelops are removed from the other side.

60

Hingedly connected to the sides 10 are doors 12 which are provided with vertically spaced longitudinal slots 13. Carried by the doors 12 are frames 14 which support the rollers 15, said rollers being arranged adjacent the slots 13, and arranged in pairs and are adapted to feed strips of stamps which are wound upon the rollers 16 which are also supported by the frames 14. Wires 17 are associated with the rollers 16 and serve to retain the stamps wound thereon. Certain of the rollers 15 are provided with knobs 18 which serve to rotate the rollers so as to feed stamps through the slots 13. It is obvious that each of the rollers 16 may be provided with stamps of any desired denomination.

75

The partition 2 forms the bottom of the compartment 7 and carries a flange 19 the purpose of which will appear later. Arranged intermediate the bottom and top of the compartment 7 is a frame 20 which has its cross bar 21 secured in the sides of the compartment and its side bars 22 secured in the partition 6, said frame being for the purpose of supporting the container 23, said container having its back 24 provided with a hook 25, while the front 26 has its upper end extended above the upper edge of the remaining walls of the container.

80

The back 24 has an eye 27 screwed thereto which is engaged by one end of the coil spring 28 the other end of which being secured to the partition 6, said spring serving to normally hold the container 23 within the compartment 7. The container 23 is particularly designed for holding stamps in book form. When it is desired to have access to the container 23 the front 26 is grasped and pulled outwardly and the container will slide outwardly upon the bars 22 until the hook 25 engages the bar 21, whereby the container can be swung to a horizontal position and at which time the bar 21 serves as a pivot.

90

A similar container 29 is mounted in the compartment 7 immediately below the container 23 and has its back provided with a hook 30 which is adapted to engage the flange 19 which forms a pivot for the container. It will be noted that the fronts of the respective containers provide closures for the open end of the compartment 7.

110

What is claimed is:—

1. A device of the class described comprising a casing, a vertical and a horizontal partition arranged within the casing and dividing the same into a pair of upper compartments and a lower compartment, hingedly mounted doors for the lower compartment, said doors having slots formed therein, frames carried by said doors and having rollers for winding strips of stamps thereon, second rollers carried by the frames for feeding the stamps through said slots, one of said upper compartments having containers mounted therein, the other of said compartments being for the purpose of receiving envelopes and postal cards, and doors for the last named compartment.
- 10
- 15
2. A device of the class described, com-

prising a casing having a vertical and a horizontal partition for dividing the casing into a pair of compartments, hingedly connected doors for one of the compartments, containers mounted in the other compartment, means for yieldably connecting the containers to the vertical partition, said containers being adapted for sliding movement into and out of the associated compartments, and means for holding the containers in tilted positions.

In testimony whereof, I affix my signature, in the presence of two witnesses.

GUY CAMPBELL.
